REFRIGERATOR CABINET

Evans T. Morton, Galesburg, Ill., assignor to Admiral Corporation, Chicago, Ill., a corporation of Delaware

Application March 30, 1954, Serial No. 419,845

7 Claims. (Cl. 220—15)

The present invention relates to refrigerators and more particularly to improved means for supporting a liner of a refrigerator in spaced relation to the outer cabinet shell.

Household refrigerators as presently constructed include an inner liner shaped to form a food compartment, an outer shell spaced outwardly from the liner, and thermal insulating material disposed between the liner and the shell. To maintain the liner securely in place, it is the practice to provide connectors between the liner and the outer shell. The air within the food compartment formed by the liner, however, is normally maintained at a substantially lower temperature than the air in the room in which the refrigerator is installed and when the connectors are formed of a thermally conductive metal, such as steel, the cold air within the liner cools the connectors. The ends of the connectors which are secured to the shell, however, are subjected to the temperature of the air in the room in which the refrigerator is located and when the warm air in the room flows in contact with the connectors, heat is conducted through the connectors to the inner liner and frequently the air adjacent the outer ends of the connector is cooled by the transfer of heat therefrom to a temperature below its dew point, thereby causing moisture in the air to collect on the shell of the refrigerator adjacent the connector. The heat conducted from the room through the connectors into the food compartment not only lowers the efficiency of the refrigerator but deteriorates the finish. The presence of moisture on the outer shell adjacent the connectors has the tendency to collect dust and its presence is annoying to fastidious housekeepers.

In the construction of the refrigerator it is desirable that the outer shell of the cabinet maintain a smooth flat surface. It frequently happens however that this surface departs from the desired flatness during fabrication due to the fact that it is thin and the door being attached to one side has a tendency to bow the side outward. Furthermore since the inner liner which forms the food compartment has to be supported from the outer shell in spaced relation thereto it also causes distortion of the outer shell. The above is particularly true during production where the tolerances are such that in some places strains are placed due to the connections of the parts.

By the present invention the outer shell of the cabinet is provided with a means which spaces the back and the front flange accurately from each other and holds the parts in rigidly spaced relation preventing any buckling or bowing of the side wall, at the same time this reinforcing means provides a most desirable support for the inner liner enabling the same to be accurately positioned within the outer liner. It also provides a most desirable means for reinforcing the shell opposite to the lock strike and shocks due to the operation thereof are taken up and transmitted to the back of the shell.

It is an object of the present invention to provide improved connectors between the liner and the shell of refrigerators by means of which the liner may be se-

2

curely maintained in place and in which the connectors are so arranged and constructed that the conduction of heat to the liner from warm air in contact with the shell of the refrigerator is minimized, thereby eliminating the formation of moisture on the outer shell of the refrigerator.

Another object of the invention is to provide one or more connectors between the liner and the shell of the refrigerator in which thermal insulating material is associated with the connectors in such a manner that the conduction of heat from the warm air in contact with the shell of the refrigerator to the food compartment of the liner is minimized.

A further object of the invention is to provide improved means for connecting the liner of a refrigerator to the shell in which the path through which heat is conducted from warm air adjacent the shell of the refrigerator to the liner is comparatively long and the conduction of heat through the connectors is impeded by the presence of thermal insulating material.

The invention will be better understood by reference to the accompanying drawings in which:

Fig. 1 is a side elevational view of a refrigerator with parts broken away to show adjacent structure, the door of the refrigerator being shown diagrammatically;

Fig. 2 is a detail elevational view of one of the front corners of the refrigerator;

Fig. 3 is a view taken on a plane passing through the line 3—3 of Fig. 2 showing parts in section and parts in elevation;

Fig. 4 is an enlarged cross sectional view taken on a plane passing through the line 4—4 of Fig. 1, looking in the direction of arrows;

Fig. 5 is a cross sectional view taken on a plane passing through the line 5—5 of Fig. 3, looking in the direction of the arrows; and

Figs. 6, 7 and 8 are enlarged cross sectional views taken on planes passing through the lines 6—6, 7—7, and 8—8, respectively, of Fig. 1, looking in the direction of the arrows.

As illustrated in the drawings, a household refrigerator of the usual type is shown including a liner 1 shaped to provide a food compartment 2, a shell 3 spaced outwardly from the liner, and thermal insulating material 4 disposed between the liner and the shell. As shown in Fig. 4, the shell of the refrigerator includes a rear wall 5 and side walls 6 and 7, side wall 6 having an inwardly extending flange 8 which is arranged in spaced relation to an outwardly extending flange 9 on the side wall 10 of the liner, and in a like manner, side wall 7 of the shell is provided with an inwardly extending flange 11 which is arranged in spaced relation to an outwardly extending flange 12 on the side wall 13 of the liner and when the parts of the refrigerator are assembled in place, breaker frames, not shown, which are formed of a plastic material having thermal insulating properties, are inserted between the outwardly extending flange on the liner and the inwardly extending flange on the shell.

According to the present invention, means are provided for securely maintaining the liner in place which are so arranged and constructed that the amount of heat which is conducted from air in the room surrounding the shell through the connectors to the inner liner is minimized and the condensation of moisture on the shell of the refrigerator adjacent to the connectors is substantially eliminated. For this purpose, connector means in the form of one or more supporting members are provided. The supporting members are preferably formed of a metal, such as steel, and are shaped to provide the desired strength. They may, for instance, be in the form of one or more channel irons arranged in the thermal insulation between the liner and each side wall of the shell which channel

irons may be supported in place and thermally insulated from at least one portion of the shell in any desirable manner. As shown, one end of each of the channel irons is connected to the rear wall of the shell and the other end is connected through thermal insulating material to the side wall or flange adjacent the front of the refrigerator. For securely maintaining the liner in place, each of the channel irons provides a support for one or more additional connectors extending between each of the channel irons and the inner liner which connectors are thermally insulated from the channel irons.

The number of channel irons which are used will of course depend upon the height of the refrigerators and the capacity of the food compartment. For large refrigerators two or more channel irons may be provided between each side wall of the liner and the side wall of the shell spaced outwardly therefrom and this is particularly true if the refrigerator is provided with two or more food compartments. As shown in the drawings, the supporting members consist of two channel irons 14 and 15 which are arranged in the thermal insulation between each side wall of the liner and the side wall of the shell spaced outwardly therefrom, and each of the channel irons is connected to the rear wall 5 of the shell adjacent one side wall thereof by suitable means, such as a pair of bolts 16 extending through an inwardly extending flange on each side wall and the rear wall 5 of the shell. Each of the channel irons is shaped to first extend inwardly to a position between each side wall of the liner and the side wall of the shell spaced outwardly therefrom and to lengthen the path of travel for heat conducted through the channel irons, each channel iron then extends at an acute angle relative to the rear wall to a position adjacent the inwardly extending flange on the side wall of the shell arranged at the front of the refrigerator. As shown, channel iron 14 extends downwardly at an acute angle relative to the rear wall, and if desired, channel iron 15 may extend in a similar direction, or it may extend upwardly at an acute angle relative to the rear wall as shown in Fig. 1.

It should be noted that the structure adapts itself to different kinds of liners. When a single liner is used, as shown in Fig. 1 the upper brace 14 will suffice to support the liner and in this instance the termination for the brace will come opposite to the door lock whereby the stresses due to locking are transmitted from the locking mechanism through the brace to the rear of the shell. In the event that two separate liners are used, as in the case where one is a freezer chamber and the other a food keeping chamber, the upper brace extends to a position to support the lower end of the upper liner and the lower brace extends to a position to support the upper end of the lower liner. The positions of the two liners bottom and top are indicated by the dotted lines L₁ and L₂ respectively in Fig. 1. It also adapts itself to structures where the freezer chest is in the lower part of the refrigerator and the food compartment in the upper. In this construction line L₃ is the bottom of the food compartment and L₄ is the top of the freezer compartment.

Each of the channel irons terminates in an outwardly extending portion 17 and thermally insulating means are provided to connect portion 17 of the channel iron to each side wall of the shell. The connecting means is similar for each channel iron and consequently only one will be described. As illustrated in Figs. 4 and 6, side wall 7 at its front end extends inwardly to form flange 11 which is provided with a reverse bend forming a strip 18 which engages flange 11 and then extends rearwardly adjacent side wall 7 of the shell as indicated by the numeral 19 and terminates in an inwardly extending arm 20 arranged parallel to flange 11 and strip 18.

The outwardly extending portion 17 of the channel iron terminates between the strip 18 and arm 20 and means are provided to connect the channel iron in substantially thermally insulated relation to the side wall 7. As shown,

an angle iron 21 is provided, one arm of which is secured to wall 7 by suitable means, such as welding, and the other arm of which engages arm 20 and a thermal insulating material 22, such as laminated material bound together by a phenolic condensation product, is interposed between arm 20 and the outwardly extending portion 17 of the channel iron, one side of which insulating material extends downwardly and engages the free end of the channel iron. Angle iron 21, arm 20, and the thermal insulating material 22, are provided with aligned openings to receive a pair of bolts 23, each of which extends through an enlarged opening in angle iron 21 and an aperture in arm 20 and is threaded in the outwardly extending portion 17 of the channel iron. It will be appreciated that since thermal breaks are provided between the channel irons 14-15 and the inner liner that the thermal break 22 may be eliminated. In this instance the member 17 would be bolted or welded directly to the flange 20.

As shown in Fig. 6, a portion of the front end of channel iron 15 is bent outwardly to form a support for a spacer 24 formed of a plastic insulating material, such as laminated material bound together by a phenolic condensation product. The spacer 24 may be secured to channel iron 15 by any suitable means, such as screws or an adhesive, and is arranged between the outwardly extending portion 17 of the channel iron and a front breaker frame which is not shown as it does not constitute any part of the present invention.

As previously stated, each of the channel irons 14 and 15 serves as a support for connectors extending between the channel iron and each side wall of the liner. The number of connectors extending between each channel iron and the liner of the refrigerator may of course be varied and will depend upon the size of the refrigerator and the capacity of the food container. As illustrated in Figs. 1 and 4, a pair of spaced connectors 25 and 26 are provided which are arranged between the liner and each channel iron, each of which is constructed to connect the liner to the channel iron and to provide thermal insulation between the channel iron and the liner.

The connector 25 is illustrated more particularly in Fig. 7 of the drawing and includes a cylindrical spacer 27 provided with a head or flange 28 having a central opening and an inwardly extending collar 29 through which a grommet 30 extends which is formed of a suitable thermal insulating material, such as rubber. The spacer 27 is also formed of a thermal insulating material which has sufficient rigidity to maintain the liner in a fixed spaced relation to the channel iron, such as laminated material bound together by a phenolic condensation product. The grommet 30 also extends through an opening in the side wall of the liner 13, the metal of the liner forming the opening being provided with an annular rim 31 which is arranged in a recess between the head 28 of the spacer and the grommet 30. To secure the parts in position, a rod-shaped member having a head and a threaded portion, such as a screw or bolt 32, is provided which extends through a cup-shaped washer 33, the lower surface of which washer bears against the outer face of grommet 30 and then through the grommet and through an enlarged opening in channel iron 14 and is threaded into a spring fastener 34 arranged interiorly of channel 14.

To prevent rotation of the spring fastener when and after the bolt 32 is threaded therein, opposite ends extend loosely through apertures in prongs or lugs 35 bent outwardly from the face of the channel iron. A rubber cap 33a having a flange engaging the liner is held in place by the cup-shaped washer 33.

The connector 26 which is arranged adjacent to the front end of the liner is somewhat similar to the connector 25. To enable the connector to yield to a sufficient extent to permit breaker frames to be inserted between the inwardly extending flanges on the side wall and the

liner, a spacer 36 is provided which is sufficiently resilient to enable the breaker frames to be easily inserted in place between the flange 11 and the liner. As shown, spacer 36 is formed of a resilient thermal insulating material, such as rubber, one end of which engages the face of channel iron 14 and the other end of which extends through an opening in the adjacent side wall of the liner. After the opening is formed in the liner, the wall of the liner surrounding the opening is bevelled inwardly as illustrated in Fig. 8 to form a recess into which one end of spacer 36 extends and the portion of the liner below the recess extends inwardly into an annular recess in the spacer.

To provide a secure connection between the wall 13 of the liner and the channel iron 14, a cup-shaped washer 37 engages the inner end of spacer 36, the outer periphery of which washer extends into the recess in the liner and a screw or threaded bolt 38 extends through a cup retainer 39, the washer 37, a central opening in the spacer 36 and an enlarged opening in the inner face of channel 14 and is held in place by a spring fastener 40 and for preventing rotation of fastener 40 when and after the bolt 38 is threaded therein, the opposite ends of fastener 40 extend through aperture on prongs or lugs 41 bent outwardly from the face of channel 14. The cup-shaped washer 39 serves to retain a suitable cap 39a in place.

Means are also arranged at each of the lower corners of the refrigerator for connecting the shell to the liner and thermally insulating the liner from the shell. For this purpose, an angle-shaped corner piece 42 is provided at each lower corner of the refrigerator, one portion of which is connected to the bottom wall 43 of the shell and another portion of which extends upwardly between the liner and shell at each corner and is connected to the liner by a suitable connector designated generally by the numeral 44.

As illustrated, each of the corner pieces 42 is provided with a downwardly extending flange 45 which is welded or otherwise secured to a flange 46 extending upwardly from the door jamb. The corner piece 42 extends inwardly and upwardly from flange 46 at an angle and then vertically and finally terminates in a horizontal flange 48 extending below the lower wall 49 of the liner and means are provided between the lower wall 49 of the liner and flange 48 for insulating the liner from flange 48 and bottom wall 43 of the shell. For this purpose, a suitable thermal insulating material, such as rubber or a plastic material, in the form of one or more blocks 50 is interposed between the liner 49 and flange 48. As illustrated, each of the blocks is provided with a recess to receive an angle-shaped portion of corner piece 42 and a hook-shaped strip 51 is provided having its hook portion engaging an upwardly extending bead 52 on the liner which is spaced inwardly from the front portion thereof. The hook-shaped strip 51 is provided with a flange 53 which extends below block 50 and with a lug 54 which extends into the block.

As illustrated in Figs. 2 and 3, a supporting member which is shown in the form of a flange 55 on corner piece 42 extends between the side walls 6 and 10, respectively, of the liner and shell and the flange on a similar corner piece, not shown, extends between the side walls 7 and 13, respectively, of the liner and shell, and means are provided to connect the liner to each of the corner pieces. For this purpose, a connector 44 arranged at each corner is provided as illustrated more particularly in Fig. 5. As shown, a thermal insulating spacer 56 which may be formed of a laminated material bound together by a phenolic condensation product, is arranged between the side wall 10 of the liner and flange 55. Spacer 56 is provided with a central opening to receive the cylindrical portion 57 of a grommet having an annular flange 58 which engages the inner face of liner 10 and a screw or threaded bolt 59 extends through a cup-shaped washer 60, the grommet, and an enlarged opening in flange 55 and is secured in place by means of a spring fastener 61.

Spring fastener 61 is held against rotation during and after bolt 59 has been threaded in place by any suitable means. As shown, prongs or lugs 62 are provided which are bent outwardly from flange 55, one of which is provided with an aperture through which one end of the spring fastener 61 extends and the other of which is provided with an aperture through which the other end of the fastener loosely extends. The cup-shaped washer 60 serves to retain a rubber cap 63 in place.

10 The channel irons 14 and 15 thus provide several functions. Since the wall 7 is relatively thin there is normally a tendency for it to bow outward or warp during assembly particularly when a door is hung on one of the walls. The channel 14 therefore serves as a brace which 15 strengthens the wall and maintains a constant spacing between the back and the front in the face of forces tending to change this spacing. Furthermore since the front ends terminate at the place where the lock strike is located, shocks due to closing the door are transmitted to the entire 20 structure rather than being localized. In addition they provide support for the liners as fully stated.

What is claimed is:

1. In a refrigerator having a liner and a shell spaced outwardly from said liner, a rigid supporting member extending from the rear portion of said shell to a position adjacent the front end thereof and being positioned throughout its extent intermediate its ends in spaced relation to said liner and shell, a connector extending between said supporting member and said liner at a position adjacent the rear portion of said liner, and a connector extending between said supporting member and said liner adjacent the front end of said shell, each of said connectors including a spacer formed of thermal insulating material engaged between the supporting member and the liner and means thermally insulated from said liner connecting the liner to said supporting member.

2. A refrigerator having a liner provided with opposite side walls, a shell surrounding the liner and having a rear portion and side walls which extend forward therefrom and terminate in front portions, one of the side walls of the shell being spaced outwardly from one side wall of said liner and the other side wall of said shell being spaced outwardly from the other side wall of said liner, two pairs of supporting members, each of the supporting 45 members of one pair being secured in spaced relation to each other to the rear portion of said shell adjacent one side wall of the shell and extending inwardly to a position intermediate one side wall of said liner and said one side wall of said shell and the other pair of supporting members being secured in spaced relation to each other to the rear portion of said shell adjacent the other side wall of the shell and extending inwardly to a position intermediate the other side wall of the liner and the other side wall of said shell, each of one pair of supporting 50 members then extending at an acute angle relative to the rear portion of said shell to a position adjacent the front portion of one side wall and each of the other pair of supporting members extending at an acute angle relative to the rear portion of the shell to a position adjacent the front portion of the other side wall of said shell, each supporting member throughout its extent being spaced a substantial distance outward from the adjacent side wall of the liner, thermal insulating material arranged between each of the first pair of supporting members and the front portion of one of the side walls of the shell and thermal insulating material arranged between each of the second pair of supporting members and the front portion of the other side wall of the shell, means associated with the thermal insulating material for connecting the front portion of each 55 side wall of the shell to each supporting member, a first pair of connectors arranged between each of the first pair of supporting members and one side wall of the liner and a second pair of connectors arranged between each of the second pair of supporting members and the other side wall of the liner, each of said connectors including a spacer

formed of thermal insulating material engaged between each supporting member and the adjacent side wall of the liner, and means for connecting each side wall of the liner to each of the supporting members at said spacers.

3. A refrigerator cabinet comprising an outer shell having a back and spaced sides extending forward from said back and having inturned flanges at their forward ends at the front of the shell, an inner liner within said shell having a back and forwardly extending opposite sides which are spaced inward respectively from the back and sides of the outer shell, a pair of rigid braces connected respectively to the back of the outer shell adjacent the respective sides of the outer shell, each of said braces extending from its connection to the back of the outer shell inward toward the inner liner and thence forward between the adjacent sides of the outer shell and the inner liner to the front of the outer shell, each brace at its forward end having a transverse portion which extends outward toward the adjacent side of the shell and is connected to the inturned flange on said side of the shell, each brace throughout its extent being spaced substantially outward from the adjacent side of the liner and inward from the adjacent side of the outer shell, a pair of first spacers of thermal insulation material respectively engaged between each brace and the respective side of the liner adjacent the back of the liner to space them apart and attachment members thermally insulated from the liner which connect the braces to the respective sides of the liner at said first spacers, and a pair of second spacers of thermal insulation material respectively engaged between each brace and the respective side of the liner adjacent the front of the liner to space them apart thereat and attachment members thermally insulated from the liner which connect the braces to the respective sides of the liner at said second spacers.

4. The cabinet of claim 3, wherein each of said second spacers is resilient.

5. The cabinet of claim 3, wherein each of said braces between the first and second spacers extends forward and downward at an acute angle with respect to the back of the outer shell, and wherein there are provided a second pair of braces connected respectively to the back of the outer shell adjacent the respective sides of the outer shell and in spaced relation below the first-mentioned braces, each of the braces of said second pair extending from its connection to the back of the shell inward toward the inner liner and then forward between the adjacent sides of the outer shell and the inner liner to the front of the outer shell, each brace at its forward end having a transverse portion which extends outward toward the adjacent side of the shell and is connected to the inturned flange on said side of the shell in spaced relation below said first-mentioned braces, each brace of said second pair throughout its extent being spaced substantially outward from the adjacent side of the liner and inward from the adjacent side of the outer shell, a pair of third spacers of thermal insulation material respectively engaged between each brace of said second pair and the respective side of the liner adjacent the back of the liner to space them apart and attachment members thermally insulated from the liner which connect the braces of said second pair to the respective sides of the liner at said third spacers, a fourth pair of spacers of thermal insulation material respectively engaged between each brace of said second pair and the respective side of the liner adjacent the front of the liner to space them apart thereat and attachment members thermally insulated from the liner which connect the braces of said second pair to the respective

sides of the liner at said fourth spacers, and each of the braces of said second pair between the third and fourth spacers extending forward and upward at an acute angle with respect to the back of the outer shell.

5 6. A refrigerator cabinet comprising an outer shell having a back and spaced sides extending forward therefrom, an inner liner within said shell having a back and forwardly extending sides which are spaced inward from the back and sides of the outer shell, a pair of rigid braces connected respectively at their back ends to the back of the outer shell and extending forward therefrom between the adjacent sides of the shell and liner and connected at their forward ends to the outer shell, each of said braces throughout its extent being spaced substantially outward from the adjacent side of the inner liner, and connectors connecting the respective braces to the sides of the inner liner, each of said connectors comprising a spacer of thermal insulation material engaged between the brace and the adjacent side of the inner liner and an attachment member which is thermally insulated between the brace and the adjacent side of the liner and which connects the brace to the adjacent side of the liner.

10 7. A refrigerator cabinet comprising an outer shell which has spaced sides, a bottom wall and a front opening above the bottom wall and between the sides, an inner liner within said shell and having spaced sides and a bottom wall in spaced relation to the sides and bottom wall of the shell, said liner having a front opening above its bottom wall and between its sides, a rigid corner piece having a lateral portion which is attached to the bottom wall of the shell and having an upstanding portion which extends upward from said lateral portion around the corner between the bottom wall of the liner and one of the sides of the liner, said corner piece projecting upward

15 30 35 between the adjacent side of the shell and said one side of the liner and being spaced from both, a connector connecting said one side of the liner to said upstanding portion of the corner piece, said connector including a spacer of thermal insulation material engaged between said one side of the liner and said upstanding portion of the corner piece and an attachment member thermally insulated from the liner which connects said upstanding portion of the corner piece and said one side of the liner, said bottom wall of the liner having a downturned flange at its forward end which terminates in a rearwardly and upwardly projecting lip, a thermal insulation member engaged between said lateral portion of the corner piece and said bottom wall of the liner, and an attachment member carried by said insulation member and presenting a forwardly and downwardly projecting lip which seats on said lip on the flange of the bottom wall of the liner.
